ASH TRAY

Ignatz Kohn, New York, N. Y.

Application December 3, 1948, Serial No. 149,939

Term of patent 7 years

(Cl. D85—2)

To all whom it may concern:

Be it known that I, Ignatz Kohn, a citizen of the United States, residing at New York, in the county of New York and State of New York, have invented a new, original, and ornamental Design for an Ash Tray, of which the following is a specification, reference being had to the accompanying drawing, forming a part thereof.

In the drawing:

Fig. 1 is a perspective view of an ash tray, showing my new design;

Fig. 2 is a vertical sectional view taken on the line 2—2 of Fig. 1;

Fig. 3 is a vertical sectional view taken on the line 3—3 of Fig. 1; and

Fig. 4 is a bottom plan view of Fig. 1.

I claim:

The ornamental design for an ash tray, as shown.

IGNATZ KOHN.
